P. A. KELLER

COLLAR

Filed June 17, 1922

INVENTOR
Paul A. Keller.

BY
Robert M. Barr.
ATTORNEY

UNITED STATES PATENT OFFICE.

PAUL A. KELLER, OF CYNWYD, PENNSYLVANIA.

COLLAR.

Application filed June 17, 1922. Serial No. 568,935.

To all whom it may concern:

Be it known that I, PAUL A. KELLER, a citizen of the United States, and a resident of Cynwyd, county of Montgomery, State of Pennsylvania, have invented certain new and useful Improvements in Collars, of which the following is a specification.

Some of the objects of the present invention are to provide an improved collar of the turn-over type; to provide a soft turn-over collar so shaped and constructed as to conform to the neck of the wearer to give a neat, well fitting appearance; to provide a soft, turn-over collar which will retain its natural shape simulating the appearance of a starched collar; to provide a turn-over collar having a finished bounding edge on the flap or turn-over portion; to provide a collar in which the use of tape or other binding material is eliminated for finishing purposes; to provide a turn-over collar having a fold line of suitable curvature to give the required shape to the collar; to provide means for concealing frayed or unfinished edges adjacent the meeting point of the fold line with the tabs at the collar ends; to provide means for securing a V shape to the meeting ends of the collar; to provide means whereby the buttonhole tabs are accurately aligned in superposed relation; to provide an improved method of forming a turn-over collar; and to provide other improvements as will hereinafter appear.

In the accompanying drawings, Fig. 1 represents the body blank of a turn-down collar embodying the present invention; Fig. 2 represents the neck band blank for the same; Fig. 3 represents one end of the blank of Fig. 1 after the first collar forming operation is complete; Fig. 4 represents the same end after the second forming operation; Fig. 5 represents an end portion of the partially formed collar with the neck band reinforcement secured in place; Fig. 6 represents the second step in securing the neck band reinforcement; Fig. 7 represents the end portion with the neck band reinforcement finally secured; Fig. 8 represents an enlarged section on line 8—8 of Fig. 7; Fig. 9 represents a front elevation of one finished end of the collar; and Fig. 10 represents a front elevation of the meeting ends of the collar in wearing position.

Referring to the drawings, one form of the present invention comprises a collar of the turn-over type formed of two pieces of

suitable material 10 and 11, each cut in a predetermined shape so that when assembled, as hereinafter described, the result will be a collar correctly fashioned as to contour, fit and appearance. The piece 10 forms the body of the collar and in its blank form provides a stand or neck portion 12, a turn-over or flap 13, and two tabs 14 for the usual buttonholes 15 (shown in Figs. 9 and 10), and is cut to the required form, from a fabric having the necessary properties to impart shape to the finished collar as well as a certain amount of stiffness to maintain such shape under wearing conditions.

The first step in the collar construction, after cutting the blank 10, is to provide a finished edge for the turn-over portion or flap 13, and this is accomplished in the present instance by stitching the edge 16 as indicated at 17, Fig. 3, with an overlock stitch or any other suitable stitch. Following this stitching operation, this edge 16, which bounds three sides of the flap 13, is then folded back upon that side of the flap 13 which forms the inner or concealed part of the flap in finished condition, to provide a relatively narrow, reinforced margin 18, Fig. 4. When so folded, a line of stitching 19 is run through the reinforcement, the stitching 17 and the body piece 10, and substantially parallel to the fold line of the margin 18 or what now becomes the finished flap edge 20 of the turn-over portion 13 as shown in Figs. 4 and 5.

Following the foregoing operations, the neck band piece 11 is superimposed upon the opposite side of the neck band portion 12 of the body fabric 10 from the marginal reinforcement 18 and temporarily stitched thereto along the outer edge. In this connection it should be noted that this neck band piece 11 has a definite predetermined shape in that its upper and lower edges 22 and 23 are curved, the former, 22, having a curvature such as to provide a fold line of the desired contour to produce a natural uniform fit about the neck of the wearer, while the latter, 23, has a curvature to snugly follow and fit the shirt neck band to which the collar is attached. Also, the neck band piece 11 is provided with tabs 24 conforming to the shape and location of the tabs 14. The lower edge 25 of the stand portion 12 of the body piece 10 is also curved to correspond to the curved edge 23 of the neck band piece 11 so that when the two parts are superim-

posed they conform substantially along the bounding edges.

In order to give a finished lower edge to the neck band and also to bring the neck band piece 11 to its proper position to be concealed by the flap 13 in folded condition, the edges 23 and 25 are turned inwardly and passed between the portion 12 and the neck piece 11, an inside out operation, which 10 brings two folded edges together on the outside and leaves the cut edges on the inside and concealed. A row of stitching 26 is then run along in close proximity to the edges, thereby forming a finished collar 15 lower edge as shown at 27. The pairs of tabs 14 and 24 have also been turned inside out during this operation as will be understood. The neck band piece 11 is now in its proper position for the finished collar, 20 namely on the same side of the body piece 10 as the marginal reinforcement 18, but has its upper edge 22 still unattached to the piece 10. In this connection it should be noted (see Fig. 6) that this edge 22 at this 25 stage of the operation overlaps the turn-over or flap portion 13 slightly, thereby extending beyond the normal fold line for the flap 13.

This overlap is shown at A, Fig. 6, where 30 its width is indicated as from the upper edge of the tab 14 to a point beyond the rough, unfinished end of the marginal reinforcement 18. By the provision of this overlap at each end, in conjunction with two nibs 35 28 (one at each end), formed during the initial cutting of the neck band blank 11, a means is provided for concealing the unsightly, unfinished end of the margin 18 and giving a neat finished appearance. This is 40 accomplished by folding the respective nibs 28 inwardly under the overlap portion of the neck band piece 11, and following that by turning the rough edge 22 inwardly under the piece 11. In this position a double 45 line of stitching 30 is run from one end of the neck band to the other, thereby securing the folded portion of the edge 22 and the nibs 28 neatly to the body piece 10. The result is an upper well defined reinforced 50 edge 31 which outlines and determines the fold line for the turn-over or flap 13. Incidental to this operation it is to be noted that the fold line is so taken as to bring it slightly 55 above the junction of the top edges of the respective tabs 14 with the body piece 10, the distance being preferably a scant eighth of an inch, as this not only insures a complete concealment of the ends of the margin 18 but, what is of equal importance, forms 60 a clearance which allows a true, accurate V shape where the ends of the collar are brought together as seen in Fig. 10. This clearance aids materially in giving the collar a correct set because the tabs 14 are free 65 to overlap without binding at the meeting

ends of the collar fold line and the button-holes 15 can be accurately superposed without stitching, binding or otherwise pulling the collar out of shape.

The over-lock stitching applied to the raw edge of the turn-over portion of the collar, in combination with the plain stitching that secures the folded edge in position, and which extends through the over-lock stitching, prevents the pulling out of the raw 75 edge of the collar in use. The application of the over-lock stitch to a single ply fabric alone would not prevent pulling out, but in combination with the folded edge and plain stitch improvement, this construction 80 forms a very efficient binder that will withstand the hard usage of modern laundry machinery.

Having thus described my invention, I 85 claim:

1. A turn-over collar comprising a body piece shaped to provide a turn-over portion and a neck band portion, the bounding edge of said turn-over portion being folded and stitched to form a reinforced and smooth 90 finished margin, a neck band piece secured to one side of said neck band portion, and nibs formed respectively at opposite ends of said neck band piece for concealing the respective ends of said margin and forming 95 a smooth edge in finished condition of said collar.

2. A turn-over collar comprising a body piece shaped to provide a turn-over portion and a neck band portion provided with end 100 tabs, a neck band piece secured to one side of the neck band portion and formed with end tabs conforming to the size and shape of said neck band tabs, and means to elevate the fold line of the body piece at each end 105 slightly above the upper junction of the edges of the end tabs and said body piece whereby a true V notch on the meeting ends of the collar in assembled position is formed.

3. A turn-over collar comprising a body piece shaped to provide a turn-over portion and a neck band portion provided with end tabs, a neck band piece shaped to conform 110 to the bounding edge of said neck band portion and having its upper edge carried 115 above the upper junction of the edges of said end tabs and body piece and stitched to said body piece to form a fold line in the body piece terminating at each end above the upper junction of the tab edges 120 therewith, and stitching uniting the bounding edges of said neck band piece and said neck band portion.

4. The method of forming a turn-over collar which consists in cutting a body piece to 125 provide a turn-over portion and a neck band portion, cutting a separate piece to conform to said neck band portion, over-lock-stitching the bounding edge of said turn-over portion, folding said stitched 130

edge, stitching said folded edge through the overlock-stitching, securing said neck band piece to one side of said neck band portion, and forming a smooth edge between said 5 body piece and said neck band piece to conceal the ends of said folded and stitched edge.

10 5. A turn-over collar comprising a body piece formed of a single blank cut to form a turn-over portion and a neck band portion, over-lock stitching on the raw edge of said turn-over portion, the edge of said turn-over portion being folded back upon itself, and plain stitching securing the folded edge in position and extending through the over-lock stitching.

15 6. The method of forming a turn-over collar which consists in cutting a body piece to

provide a turn-over portion and a neck band portion, cutting a separate piece to conform to said neck band portion, overlock stitching the bounding edge of said turn-over portion, folding said stitched edge, stitching said folded edge through the over-lock stitching, securing said neck band piece 20 to one side of said neck band portion by stitching it along one marginal edge, reversing the positions of said body piece and neck band piece by turning the parts inside out, and stitching the other marginal edge 25 of said neck band piece to said body piece.

Signed at Philadelphia, in the county of Philadelphia, and State of Pennsylvania, this 14 day of June, 1922.

PAUL A. KELLER.
